CLAIM

The ornamental design for a travel altar with unfolding table, as shown and described.

DESCRIPTION

FIG. 1 is a perspective view of a travel altar with unfolding table, showing my new design in an open position;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of the travel altar with unfolding table in an alternate closed position.

1 Claim, 5 Drawing Sheets
